UNITED STATES PATENT OFFICE

DONALD R. DE TAR, OF SCHENECTADY, NEW YORK, ASSIGNOR TO GENERAL ELECTRIC COMPANY, A CORPORATION OF NEW YORK

TUNING DEVICE FOR RADIO APPARATUS

Application filed June 6, 1927. Serial No. 196,742.

My invention relates to tuning devices for radio apparatus, and has for its principal object the provision of an improved tuning device that will operate smoothly without slippage or backlash.

In the operation of radio receiving apparatus, it is desirable that the variable condenser or other tuning device of the apparatus be driven through some form of speed-reducing mechanism in order that a condition of exact resonance with any given broadcasting station may be readily produced. Various forms of gear and friction drives have been provided for this purpose in the past, but these drives have not been altogether satisfactory for the reason that the gear drives do not operate without backlash and the friction drives are likely to slip, especially after being used for some time. In accordance with my invention these difficulties are avoided by means of a tuning device provided with a drive mechanism which comprises a flexible member positively attached to the movable member of the device and arranged to be maintained substantially taut under all conditions of operation.

My invention will be better understood from the following description when considered in connection with the accompanying drawings and its scope will be pointed out in the appended claims.

Referring to the drawings Fig. 1 illustrates a tuning device wherein my invention has been embodied and Fig. 2 shows certain details of the device illustrated by Fig. 1.

This device comprises a plurality of variable condensers each provided with a rotor 1 mounted on a shaft 2 and with a stator 3 mounted in a tub-shaped support 4. Adjustment of the different condensers is effected by a drive mechanism comprising a pulley 5 mounted on the shaft 2 and provided with grooves adapted to receive a small metal cable 8 through which it is coupled to a pair of grooved drums 6 and 7. The drums 6 and 7 are mounted on a shaft 9 which is arranged to be rotated by a knob 10 in bearings formed by a member 11 attached to the support 4. In order to maintain the length

tially constant for all adjustments of the rotors 1, the drums 6 and 7 are so arranged with respect to the pulley 5 that the cable at opposite sides of the pulley 5 makes equal angles with the vertical axis of the shaft 2 when the points of tangency between the drums and cable are in the middle of their travel. As illustrated, these points of tangency move in the same direction along the axes of the drums.

Between the grooved drums 6 and 7, the cable 8 passes along a groove near the left hand edge of the pulley 5, through a notch 12 to the inner periphery of the pulley, through a notch 13 to a groove near the right hand edge of the pulley, under a tightening lug 14 and further along a groove near the right hand edge of the pulley to the drum 7. It will be apparent that the connection of the cable between the grooves 12 and 13 have the effect of anchoring it to the pulley 5 so that it can not slip in the grooves. Under these conditions, the tension of the cable 8 is dependent on the adjustment of a screw 15 which holds the lug 14 in contact with the cable, and slippage of the cable in the grooves of the drum is prevented. Between the grooves on the drum 5 is supported an outer cylindrical member 16 to which a log sheet 17 may be attached by means of screws 18 and 19 for the purpose of logging the tuning position for different stations. The weight of the rotors 1 is counterbalanced by a counterweight 20 and a stop 21 is arranged to cooperate with stops on the left hand side of the pulley 5 for the purpose of limiting the rotation of the shaft 2. It will of course be understood that all of the tuning device except the knob 10 may be mounted within a casing and that an opening may be provided in the casing for reading the log sheet 17.

Assuming the various parts of the tuning device to be in their illustrated positions, rotation of the knob 10 in a clockwise direction causes the cable 8 to wind from the drum 6 onto the drum 7, thus rotating the pulley 5 and the shaft 8 in a clockwise direction. Rotation of the knob 10 in a counterclockwise direction causes the cable to wind from the

drum 7 onto the drum 6 and produces counterclockwise rotation of the shaft 2. As previously indicated, the cable 8 is preferably so arranged that its points of tangency move along the drums 6 and 7 in the same direction and variation in the length of cable between the drums is avoided by so arranging the drums with respect to the pulley that the points of tangency between the cable and

10 drums move through equal distances with respect to the vertical axis of the shaft 2 as the knob 10 is rotated. It has been found that with these precautions the tautness of the cable is substantially constant through

15 the operating range of the device and the condensers are adjusted from one position to another without slippage or backlash.

What I claim as new and desire to secure by Letters Patent of the United States is:

20 1. In a radio apparatus, the combination of a pulley provided with peripheral grooves near its opposite edges, a tuning device mechanically fixed to said pulley, rotatable drum means, a single flexible cord member arranged to lie in and be anchored between said grooves and arranged to be simultaneously wound on and unwound from said rotatable drum means, an outer cylindrical member attached to the periphery of said

25 pulley, and means for attaching a log sheet to said cylindrical member.

2. In a radio apparatus, the combination of a pulley provided with peripheral grooves near its opposite edges, a tuning device comprising a rotor mechanically fixed to said pulley, rotatable drum means, a single flexible cord member arranged to lie in and be anchored between said grooves and arranged to be simultaneously wound on and unwound from said rotatable drum means, an outer cylindrical member attached to said pulley concentrically therewith, and means attached to said pulley and mounted in the space between said pulley and the outer cylindrical member for counterbalancing the weight of said rotor.

3. A radio apparatus including a condenser rotor mounted on a rotatable shaft, a pulley provided with peripheral grooves near its opposite edges, a pair of rotatable drums, a single flexible cable arranged to lie in and extend between said grooves and to be simultaneously wound upon one of said drums and unwound from the other of said drums, and a single stop arranged to limit the rotation of said pulley in either direction.

4. A radio apparatus including a condenser rotor mounted on a rotatable shaft, a pulley provided with peripheral grooves near its opposite edges, a pair of rotatable drums, a single flexible cable arranged to lie in and extend between said grooves and to be simultaneously wound upon one of said drums and unwound from the other of said drums, and

65 adjustable means including a movable lug

attached to said pulley and engaging the cable intermediate its ends for adjusting the tension of said cable throughout its length. In witness whereof, I have hereunto set my hand this 3d day of June, 1927.
